Patented Nov. 9, 1920.

FIG. 1

FIG. 2

INVENTOR.
LOUIS MANDEL
BY *Ed. Jochum Jr.*
ATTORNEY

UNITED STATES PATENT OFFICE.

LOUIS MANDEL, OF CHICAGO, ILLINOIS.

FLEXIBLE OPERATING OR TRIPPING MECHANISM.

1,358,011.

Specification of Letters Patent. Patented Nov. 9, 1920.

Application filed December 20, 1919. Serial No. 346,409.

To all whom it may concern:

Be it known that I, LOUIS MANDEL, a citizen of the United States, residing at Chicago, in the county of Cook and State of Illinois, have invented certain new and useful Improvements in Flexible Operating or Tripping Mechanism, of which the following is a specification.

This invention relates to improvements in flexible operating or tripping mechanism commonly known as "Bowden wire," particularly adapted though not necessarily limited in its use under conditions where it is desired to set in motion, operate or trip an element or part from a remote point and particularly where the space in which the tripping mechanism is small or limited and under conditions where the tripping mechanism is not always maintained in a straight line.

A further object is to provide an improved device of this character which will be extremely light, compact and durable in construction and embodying a flexible, inextensible or incompressible and non-metallic element within and substantially filling the outer casing so that the axes of the said outer and inner elements will always coincide in any position to which the elements may be bent.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which;

Figure 1 is a view partly in elevation and partly in section of an improved device of this character constructed in accordance with the principles of this invention.

Fig. 2 is an elevation showing the parts twisted.

Referring more particularly to the drawing the numeral 10 designates generally a hollow flexible inextensible and incompressible outer casing which is constructed of any suitable material and of any desired size and configuration but preferably embodies a flexible housing 11 preferably covered with suitable fabric 12 or if desired the fabric may be omitted. At one end of the housing there is provided an element 13 by

means of which the end of the housing may be connected with any fixed support and at the other end of the housing there is provided another element 14 by means of which the end of the housing may be 60 grasped and held. Within the housing thus formed is a flexible inextensible and incompressible non-metallic element 15 which is constructed of any suitable material such as cat-gut or other animal fiber, or vegetable 65 fiber such as cord, rope or the like. This element 15 is of a diameter to substantially fill the housing 10 and connected to one end of the element 15 is an element 16 which is adapted to reciprocate within the element 70 13 and the extremity 17 of the element 16 is adapted to be connected with the part which is to be set into motion, operated or tripped, and the portion 17 of the element 16 preferably projects beyond the end of the 75 element 13.

At the other end of the element 15 and adjacent the element 14 so as to reciprocate therein is another element 18 which preferably projects beyond the element 14 and 80 may be provided with a portion 19 which is adapted to be grasped by the hand so that the operator in operating the device will hold the element 14 in one hand and the element 19 in the other hand. In this position and 85 by imparting a relative longitudinal shifting movement of the elements 19-14, it will be manifest that there will be a similar relative longitudinal movement imparted to the elements 10-15. Inasmuch as the element 90 15 substantially fills the casing or element 10, it will be manifest that the element 15 cannot become kinked or distorted in any manner that would prevent it from sliding freely within the casing 10. Inasmuch as 95 the element 15 and the casing 10 are both of a flexible nature these elements may be flexed or twisted in any manner without impairing the free longitudinal shifting movements of the two elements with respect to each other. 100

If desired there may be provided a spring 20 within the element 14 which tends normally to return the parts to their normal position.

With this improved construction it will be 105 manifest that by reason of the fact that the element 15 is bound throughout substantially its entire length by the closely fitting casing 10, the element will not kink or be distorted with respect to the casing and 110

thereby the longitudinal shifting movement will not be affected.

While the preferred form of the invention has been herein shown and described, it is to be understood that various changes may be made in the details of construction and in the combination and arrangement of the several parts within the scope of the claims without departing from the spirit of this invention.

What is claimed as new is:—

1. A tripping or operating mechanism of the character described embodying a transversely flexible inextensible and incompressible casing, a transversely flexible inextensible and incompressible non-metallic element within and substantially filling the casing, means respectively at one end of one of the elements for anchoring it and at the adjacent end of the other element for connecting the latter with the part to be set in motion or tripped, and means respectively at the other ends of the elements whereby a relative longitudinal movement of the elements may be produced.
2. A tripping or operating mechanism of the character described embodying a transversely flexible inextensible and incompressible casing, a flexible incompressible elastic element within and substantially filling the casing, means respectively at one end of one of the parts for anchoring it and at the adjacent end of the other part for connecting the latter with the part to be set in motion or tripped, and means respectively at the other ends of the elements whereby a relative longitudinal movement of the elements may be produced.

a relative longitudinal movement of the elements may be produced.

3. A tripping or operating mechanism of the character described embodying a transversely flexible inextensible and incompressible casing, a flexible incompressible fibrous element within and substantially filling said casing, means respectively at one of the ends of one of the parts for anchoring it, and at the adjacent end of the other part for connecting it with the part to be set in motion or tripped, and means respectively at the other ends of the parts whereby a relative longitudinal movement of the elements may be produced.

4. A tripping or operating mechanism of the character described embodying a transversely flexible inextensible and incompressible casing, a transversely flexible inextensible and incompressible non-metallic element within and substantially filling the casing, means respectively at one end of one of the elements for anchoring it and at the adjacent end of the other element for connecting the latter with the part to be set in motion or tripped, means respectively at the other ends of the elements whereby a relative longitudinal movement of the elements may be produced, and a spring element interposed between the said casing and the first recited element for returning the parts to their normal relative positions.

In testimony whereof I have signed my name to this specification, on this 29th day of November, A. D. 1919.

LOUIS MANDEL
